UNITED STATES PATENT OFFICE.

HARRY SISKIN, OF LOS ANGELES, CALIFORNIA.

CEDAR-CHEST BED.

1,142,537.

Specification of Letters Patent.

Patented June 8, 1915.

Application filed June 4, 1914. Serial No. 842,855.

To all whom it may concern:

Be it known that I, HARRY SISKIN, a citizen of the United States, residing at Los Angeles, in the county of Los Angeles and 5 State of California, have invented a new and useful Cedar-Chest Bed, of which the following is a specification.

This invention relates to an article of household furniture having various uses.

10 An object of this invention is to provide a piece of household furniture designed to serve for the safe and clean storage of a bed and bedding including woolen blankets or the like liable to injury from moths; and 15 also for the storage of furs and woolen clothing likely to be injured by moths; and to conceal the bed in a novel manner with minimum expense and in minimum space.

An object of the invention is to store the 20 bed in a portable housing that is unobtrusive; that does not suggest the presence of a bed; that is as compact and portable as may be possible, and that in addition to its character as a bed, serves the purpose of 25 conveniently storing articles of clothing to occupy the small amount of space which might otherwise be wasted.

An object of the invention is to provide 30 means whereby a dormitory or barracks having a large number of beds may be cleared of said beds and the beds stored in a minimum space leaving the rest of the dormitory or barracks free for ballroom and like purposes.

By this invention I provide a masked bed 35 of cheap and simple construction having a dirt, dust and moth proof compartment suitable for storing clothes and the like, the compartment being mounted at the top of the bed when the article is folded in chest form, 40 instead of underneath the bed; thereby avoiding the dropping of dust and dirt into the compartment from the bed.

An object is to produce a bed of this class 45 that requires very little room in storing and shipping and one in which the beds may be stored one on top of another similar to trunks without danger of marring or damaging, this feature being especially desirable in connection with rooming houses and 50 hotels where extra beds are often needed on short notice.

Another object is to construct a chest bed in which the assembled bed requires practically no more room for shipping purposes

than if knocked down, so that a bed may be 55 built and completely assembled at the factory and then shipped, without crating, direct to the user; thus avoiding the work of assembling and crating on the part of the shipper; also to provide an article of this 60 class that can be very readily handled and easily moved through doors from one room to another without taking apart.

The features, capabilities and advantages 65 of this invention will be apparent from the detailed, subjoined description of one specific embodiment thereof.

The accompanying drawings illustrate the invention.

Figure 1 is a perspective view of a chest 70 bed embodying this invention and shown closed in chest form. Fig. 2 is a perspective of the same bed with the chest lid raised, affording access to the clothes compartment. Fig. 3 is a perspective showing the chest 75 bed turned into bed form, the rear portion of the mattress being rolled over for clearness of illustration. Fig. 4 is a transverse section on line x^4-x^5 , Figs. 1 and 6, the article being shown in chest form and the 80 bed intact. Fig. 5 is a section in the same plane as Fig. 4, showing the device partly extended into bed form. Fig. 6 is a plan view of the bed in chest form, portions being broken away to expose construction 85 otherwise hidden.

The hollow open chest-bed body is constructed of a front side wall 1 of a definite height, and a back side wall 2 and two end walls 3 of a greater height than the front 90 wall; the end walls and back wall being of equal height with each other. Said end walls may be variously formed and are shown in the drawings as having a panel a and border reinforcements b and c at the 95 sides and top respectively of the end wall panels a .

At the rear side of the body, a top board 4 is provided extending over the top edge of the back wall and across the end walls near 100 the back wall and also over a rear portion of the hollow space of the chest body.

In front of the top board the hollow chest lid is arranged, the same being constructed of the side sections 5, 6 and end sections 7. 105 The front section 5 extends from end wall to end wall and is of a definite height extending from the top of the front wall 1 to the

level of the tops of the end and back walls. The tops of the front and back sections 5, 6 and end sections 7 are in a common plane and a top strip 8 equal in thickness and 5 length to the top board 4 is fixed to the top of the back section 6 and the end sections 7 of the hollow lid and to said top strip 8, there is hinged by hinges 9, the top lid 10, which is a board equal in thickness and 10 length to the top strip 8 and top board 4. The hollow top lid is also provided with a bottom 11, the lower side of which is above the level of the front section 5 but is flush with the inner section 6 of said hollow lid. 15 The hollow lid is hingedly connected with the chest body by a folding bed construction which may be of any suitable form jointed together in such a manner as to fold into the chest body below the top board 4 and 20 below the level of the lid bottom 11 when said chest is closed.

The form of folding bed shown comprises the bed rail sections 12, 13, 14, 15 and 16; said sections being pivoted together and the 25 section 12 being connected by the angle member 17 and pivots 18, 19 with the inside reinforcements 131 of the end walls 3; the bed rail section 13 being hinged to the hollow lid by the members 20, 21, 21', 22 there being standard members 22 fixed to the end walls 3 to pivotally support the hinge members 21' and a tie member 23 between the angle member 17 and the member 20 in a well-known manner, the member 21 being 35 connected with the section 14 and the outer edge of the hollow lid, the construction being such that the bed frame may be doubled up with the mattress 24 inside the same as seen in Fig. 4. The foldable bed frame is 40 provided with the usual legs 25, see Figs. 3 and 5, pivoted to the section 16 to fold with relation to the bed frame; and the edge of the hollow lid is provided with legs 26 that are foldable thereon to be housed within the 45 closed chest when the bed is folded into the chest body and the hollow lid is closed down. The end sections 7 of the hollow lid extend down below the level of the bottom 11 when the lid is in chest closing position.

50 Inside of the chest body at the ends thereof are provided the end supports 3" upon which the bottoms of the end sections 7 rest when the appliance is closed as shown in Fig. 4.

55 A spring latch 28 fixed to the underside of the top board 4 is adapted to engage a catch 29 on the inner edge of the hollow lid when said lid is closed; a lock 30 is provided to engage catches 31 on the top lid 10, 60 to lock the same in its closed position so that when the hollow lid is reversed, as shown in Fig. 5, the contents will be securely held inside the hollow lid.

65 A latch pull 32 between the top board and its adjacent side wall 2 is provided to dis-

engage the catch 29 preparatory to extending the hollow lid from its closed position as indicated in Fig. 4.

In practical operation when the bed is folded into the chest body, as shown in Fig. 70 4, the hollow lid may be closed and the chest with its contained bed is brought into a minimum space and can be stored as desired, one upon another in the most compact manner, the key 33 being removed after the top 75 lid or closure 10 is locked.

The compact chest-like contrivance formed by closing the chest, as shown in Figs. 1 and 4, permits of the storage of the bed in the easiest and most compact manner. 80

It is understood that the chest may be made of various sizes, and a convenient size is constructed by making the end walls twenty-nine inches across from front to rear wall and eighteen inches or more high as 85 may be desired, the first chest wall 1 being eight inches wide and from three feet to six feet eight inches long, more or less, while the rear wall 2 is the same length as the front wall 1 and the same height as the end walls 90 3. The top lid 10, which is uppermost when the chest is closed, may be twenty-two inches wide from the hinges 9 to the free edge 34. The end walls are provided with handles 35 by which the chest can be easily moved from 95 place to place when the bed is in storage and the lid closed and locked.

The chest frame may be provided with casters 36 to roll on the floor.

The chest body and the hollow lid are 100 adapted to be made of cedar so as to exclude moths and the appearance of the folded bed may thus be that of a cedar chest adapted for a window seat or a cozy corner seat.

It is evident that the chest may also be 105 made of any kind of wood or other suitable material to suit the demands of trade.

I claim:

1. A double lidded chest, one of the lids of which is hollow and is hinged to the body 110 of the chest to form a supplemental compartment over the main compartment of the chest when such lid is closed, and the other lid forming a closure for the compartment in the hollow lid and also forming a top of the chest when the chest is closed and a foldable bed and members hingedly connecting the hollow lid and the chest body together, said bed folding into and housed within the space below the bottom of the hollow lid 115 when the chest is closed.

2. A chest body having a front wall of a determined height, and end walls and back wall of a greater height; a top board extending over the rear of the end walls and the space between said walls; a hollow lid extending from the top level of the front wall to the level of the end and back walls, a lid for the hollow lid; means to fasten the lid in hollow-lid closing position; and a folding 125 130

bed frame and members hingedly connecting the hollow lid and the chest body together; said lid and the top board forming the chest top when the chest is closed.

- 5 3. A chest bed comprising an open frame having a front wall of a definite height and a back wall and two end walls of a greater height, said frame being open at top and bottom, a hollow lid in hinged relation to
10 said frame to form a closure for the top of

the frame, a foldable bed frame and members hingedly connecting the hollow frame and the hollow lid together.

In testimony whereof, I have hereunto set my hand at Los Angeles, California this 15
29th day of May, 1914.

HARRY SISKIN.
